STAIR CONSTRUCTION

Application filed April 11, 1929. Serial No. 354,404.

This invention relates to improvements in stair construction, and has for its object to provide a stair construction of strong and rigid construction which may be easily and quickly assembled and which will be entirely fireproof.

The invention consists in a stair construction as set forth in the following specification and particularly as pointed out in the claims thereof.

Referring to the drawings:

Figure 1 represents a plan view of a section of a staircase embodying our invention.

Fig. 2 is a vertical section taken on the line 2—2 of Fig. 1.

Fig. 3 is a vertical transverse section taken on the line 3—3 of Fig. 1.

Fig. 4 is a detail section taken on the line 4—4 of Fig. 3.

Fig. 5 is an enlarged side elevation of a portion of one of the stringers illustrating the method of interlocking a tie bolt with the stringer.

Fig. 6 is a view similar to Fig. 5 illustrating another method of interlocking a tie bolt with a stringer.

Like numerals refer to like parts throughout the several views of the drawings.

In the drawings, referring to Figs. 1 to 5 inclusive, 10 and 11 represent the side stringers of a staircase, the stringer 10 being located adjacent to the side wall 12 of a building and the stringer 11 being located upon the opposite side of the staircase from the stringer 10. The stringers 10 and 11 are preferably of channel construction, and rigidly secured thereto upon their undersides are narrow plates 13 which are preferably welded to the lower flange of the channel. The plates 13 extend beyond the closed side of the channel, thereby in effect forming a T at the lower side of the channel. The purpose of the plates 13 is to provide a flange for the closed side of the channel which will have parallel upper and lower sides, it being impossible to obtain any standard channels or angles that have flanges with parallel sides and that do not have fillets where the flange joins the main portion of the channel.

Extending between the stringers 10 and 11 and resting upon and having close contact with the entire upper surface of the portion of the plates 13 that project from the stringers is a tread support 14. The tread support 14 is constructed of sheet metal and is secured to the plates 13 by bolts 15 and the opposite side edges of the tread support abut against the inner face of each of the stringers.

The tread supports 14 are bent upwardly at 16 to form the front edge of the tread portion of the stairs and the upwardly bent portion 16 is bent rearwardly at 17 in order to reinforce the upper front corner of the tread portion. The tread support 14 at the rear thereof is bent upwardly at 18 to form the riser for the stairs and the upper portion of the riser is bent rearwardly at 19 to form a flange which is bolted to the adjacent tread support 14 by bolts 20.

In addition to being secured together by the tread support 14, the stringers 10 and 11 are tied together by means of bolts 21 which extend through and between said stringers above the horizontal portion of the tread support 14 below the level of the flange 17. In order that the bolts 21 may be easily secured to the stringers 10 and 11, said bolts are provided with specially formed head portions 22 which are insertable through slots 23 provided in the stringer 10. The bolts 21 are inserted through the stringer 10 from between the stringers 10 and 11 and after the head portion 22 of the bolt has been inserted through the slot 23 and pushed toward the wall 12 a sufficient amount to permit the opposite end of the bolt to be inserted through a hole provided therefor in the stringer 11 the bolt is rotated one quarter of a turn in order that the head portion 22 will interlock with the stringer 10 as illustrated in Fig. 5, after which a nut 24 is applied to the end of the bolt that projects through the stringer 11. After the bolts 21 are in position, concrete or any other suitable form of a temporary plastic material 25 is placed upon the tread support 14 to form the tread portion of the stairs and the upper surface of the tread

portion is flush with the upper surface of the flange 17. The concrete or other material 25 flows around the rods 21 and after the material is set, the rods act to hold said material firmly in position upon the tread support.

By securing the plates 13 to the under sides of the channels 10 and 11, it is possible to secure the tread supports 14 to the plates 13 with the under surface of the tread support contacting directly with the upper surface of the plates 13 as illustrated in Fig. 4 and at the same time the absence of a fillet where the upper surface of the plate 13 intersects the closed side of the channel makes it possible for the opposite edges of the tread support to abut against the adjacent face of the stringer, giving a tight joint that will hold the concrete, or other plastic material, when the same is poured upon the tread support.

By providing the slots in the stringer 10, it is possible to insert the bolts 21 in the stringers from a position between said stringers after the latter have been placed in position, and after the bolts are in their final positions the stringers 10 and 11 are tied directly together, the material 25 is prevented from lifting and the bolts are, in turn, prevented from moving in the slots by the material 25.

In Fig. 6 we have illustrated another form of slot 26 that may be provided in the stringer 10. This slot has an enlarged portion 27 through which the ordinary head 28 of a standard form of bolt 29 may be inserted, after which the bolt may be moved laterally thereof into a narrow portion 30 of the slot. By providing this form of slot, the bolt 29 may be inserted in the stringers 10 and 11 in exactly the same manner as the bolts 21 previously described, and it is not necessary to provide a special head for the bolt as is the case where the slot is formed as illustrated in Fig. 5.

We claim:

1. A stair construction having, in combination, a pair of side stringers, a sheet metal tread support mounted upon said stringers and extending therebetween, bolts extending through and between the stringers above the tread support and spaced apart from the surfaces of the latter and tying the stringers together, and a temporarily plastic material upon said tread support and surrounding said bolts and constituting the tread portion of the stairs.

2. A stair construction having, in combination, a pair of side stringers, a plate fastened to the under side of each stringer, a sheet metal tread support fastened to and resting upon the upper surface of said plates with its opposite edges abutting against the adjacent face of both of said stringers, bolts extending through and be-

tween the stringers above the tread support and spaced apart from the surfaces of the latter and tying the stringers together, and a temporarily plastic material upon said tread support and surrounding said bolts and constituting the tread portion of the stairs.

3. A stair construction having, in combination, a pair of side stringers, one of said stringers having slots provided therein, a sheet metal tread support mounted upon said stringers and extending therebetween, bolts extending through and between the stringers above the tread support and having head portions insertable through said slots, and a tread portion of concrete upon the tread support and surrounding said bolts.

In testimony whereof we have hereunto set our hands.

ABRAHAM E. SHLAGER.
LOUIS SHLAGER.
BENNETT M. GROISER.
